(57) **CLAIM**

The ornamental design for a pocket solar panel charger, as shown and described.

DESCRIPTION

FIG. 1 is a front perspective view of a pocket solar panel charger;

FIG. 2 is a front view thereof;

FIG. 3 is a back view thereof;

FIG. 4 is a top view thereof;

FIG. 5 is a bottom view thereof;

FIG. 6 is a right-side view thereof;

FIG. 7 is a left-side view thereof;

FIG. 8 is a front perspective view of a second embodiment of a pocket solar panel charger;

FIG. 9 is a front view thereof;

FIG. 10 is a back view thereof;

FIG. 11 is a top view thereof;

FIG. 12 is a bottom view thereof;

FIG. 13 is a right-side view thereof;

FIG. 14 is a left-side view thereof;

FIG. 15 is a front perspective view of a third embodiment of a pocket solar panel charger;

FIG. 16 is a front view thereof;

FIG. 17 is a back view thereof;

FIG. 18 is a top view thereof;

FIG. 19 is a bottom view thereof;

FIG. 20 is a right-side view thereof;

FIG. 21 is a left-side view thereof;

FIG. 22 is a front perspective view of a fourth embodiment of a pocket solar panel charger;

FIG. 23 is a front view thereof;

FIG. 24 is a back view thereof;

FIG. 25 is a top view thereof;

FIG. 26 is a bottom view thereof;

FIG. 27 is a right-side view thereof; and,

FIG. 28 is a left-side view thereof.

The broken lines shown represent unclaimed subject matter and form no part of the claimed design.
